ANCHOR

Chester R. Pieper, Warrenton, Mo.

Application January 13, 1944, Serial No. 518,059

5 Claims. (Cl. 189—92)

My invention relates to improvements in anchors for securing the ends of guy cables and the like, and particularly to improvements in expansion type guy anchors. Such anchors are chiefly characterized by blade members which are adapted to be folded together to permit the anchor to be installed in a previously formed hole of relatively small diameter, and thereafter to be extended laterally to penetrate and obtain anchorage in the undisturbed earth at the sides of the hole.

The principal object of my invention is to provide an improved anchor of the type aforesaid, the invention being chiefly directed to improvements which simplify the construction and reduce the manufacturing costs of the anchor. This object is accomplished by an improved sheet metal blade structure formed as a single, integral stamping, and wherein special provisions for hinge connections between the individual blades, such as are employed in former expansion anchors, are entirely eliminated.

Other objects reside in the provision of an improved strain plate which functions to reinforce the blade arms to distribute the load forces uniformly thereto, and to lock the blade arms in distended positions; and the provision of an improved cap plate which overlies the inner ends of the blades and serves to receive and transmit thereto impact forces applied for spreading and setting the blades.

These and other objects and advantages of my improved anchor construction will appear from the following description wherein reference is made to the accompanying drawing in which:

Fig. 1 is a top plan view of the earth anchor with the blade arms distended;

Fig. 2 is a side elevational view of the device of Fig. 1;

Fig. 3 shows the device with the blade arms in folded positions;

Fig. 4 is a side view of the cap or percussion plate, and

Fig. 5 is a top plan view of the bottom, or strain plate.

Referring now to the drawing by characters of reference, my improved anchor embodies a blade structure having blade arms or earth-engaging lobes designated 10, a bottom disc 11 to which is attached the anchor rod 12, and a cap or percussion plate 13.

The blade arms or lobes 10 are formed integrally, preferably from a single oblong piece of heavy gage sheet metal. In forming the blades the oblong sheet metal blank is provided with a cen-

tral opening 14, which opening may be rectangular as shown and elongated in the direction of the transverse axis of the blank. In producing the opening 14, metal lips 15 extending along opposite sides of such opening are folded back upon the adjacent metal, these lips forming abutments for the percussion plate 13 and serving to strengthen and rigidify those areas which receive the impactive blows applied for spreading the blade arms. Substantially T-shaped recesses 16 in the side edges of the blank are aligned with the central opening 14 in the transverse axis of the blade unit. There remains between openings 14 and 16 relatively narrow necks of metal 17 by which the blade arms 10 are integrally united.

The blades 10 have rounded end margins 18 and are curved longitudinally as shown. These features enable the blades to be driven cleanly and with a minimum of disturbance into the earth at the sides of a hole preformed to receive them, the blades being constrained to an accurate path of movement as they are spread apart from the initial, compact arrangement appearing in Fig. 3, to the distended positions shown in Fig. 2. The blades are considerably strengthened by the formation therein of longitudinal ribs, certain thereof, designated 19, protruding from the upper surface of the blades, and others, designated 20, being depressed below the normal plane of the blade. Shoulders 21 are produced at the inner ends of ribs 20, and after the blade arms are distended these shoulders seat against the circumferential edge of the bottom disc 11 whereby the blade arms are caused to be locked in distended position.

The bottom disc 11 is preferably a casting and is formed to provide flat top surface 23 which slopes downwardly from a diametral ridge 24, toward opposite sides of the disc. A central opening 25 is surrounded by a depending annular flange 26, and parallel ribs 28 traverse the under surface of the disc. These ribs are located so as to be in alignment with the blade ribs 20 and serve to reinforce the disc against lateral compressive forces imparted thereto by the blades. It will be seen that the anchor rod 12 extends through the opening 25 in the bottom disc, which member is retained on the rod by a nut 27.

The top plate 13 is attached to the blade member by means of end lugs 28 which extend through the openings 16 and are bent under the adjacent neck portions 17. A central opening 29 in plate 13 accommodates the anchor rod 12 which is at all times held centered with respect to the larger opening 14 in the blade unit. The top plate fur-

ther aids in maintaining a uniform angular relationship between the anchor rod and the several blade arms 10 as the latter are being expanded. Additionally, the top plate 13 serves as an anvil or strike plate and as such it receives the blows from a percussion tool and transmits the impact forces uniformly to the elevated central portion of the blade unit (Fig. 3). As the central portion is forced downwardly, accompanied by a straightening of the connecting neck portions 17, the blade arms are caused to spread. In full open position, Fig. 2, the sloping disc surfaces 23 flatly abut the adjacent under surfaces of the blade and the shoulders 22 engage the periphery of the disc, whereby to prevent collapsing of the blade arms when tension is applied to the rod 12. The plate 13 has another function in that it presses downwardly on the extreme inner ends of the blade arms and resists the tendency of the inner portion of the blade arms to rise off of the bottom disc when an upward force is applied to the rod. It will be understood that after the anchor has been expanded, soil is packed in place about the rod and over the plate 13. The weight and resistance of the earth presses downwardly on plate 13 and acts through plate 13 on the inner extremities of the blade arms, thus increasing the effectiveness and holding power of the anchor.

Having described my improvement what I claim and desire to secure by Letters Patent is:

1. An earth anchor including an anchor rod and a spreader disc thereon, an expandable blade structure on the rod above the spreader disc, comprising an elongate sheet metal stamping having a central opening, and openings spaced on opposite sides of said central opening, a top plate overlying the central area of said stamping, said top plate having an opening through which the anchor rod extends and depending lugs at opposite ends that extend through and embrace marginal portions of said side openings.

2. An earth anchor of expansion type comprising an integral blade structure having oppositely disposed lobal portions, a rod extending centrally through the blade structure, a strain plate secured to said rod below the blade structure and a percussion plate slidable on said rod, said percussion plate having integral lugs at opposite ends depending through openings in the blade structure and serving to secure and fix the position of said percussion plate relative to the blade structure.

3. An earth anchor of expansion type, opposed blades connected together by bendable straps integral therewith, the inner marginal portion of said blades being turned back to provide a reinforced striking edge, a strain plate, projections on the under blade surfaces for engaging said strain plate, a rod secured to the strain plate and extending through an opening in the blade structure, said opening being located between said reinforced inner margins, and a percussion plate having an opening through which said rod extends, said percussion plate opening being of size snugly to accommodate said rod, and means connecting said percussion plate to the blade structure.

4. An earth anchor of expansion type, comprising a blade structure formed of sheet metal and having opposed lobes interconnected by spaced neck portions formed integrally with the lobes, an anchor rod extending through the space between said neck portions, a strain plate secured to the rod below the blade structure, a percussion plate mounted on the rod above the blade structure, said percussion plate having depending lugs engaging said neck portions, the inner marginal portions of the lobes being doubled back to provide abutments for said percussion plate.

5. In an earth anchor of expansion type, a blade structure comprising an integral sheet metal stamping formed to provide oppositely disposed earth-engaging lobes interconnected by a pair of laterally spaced neck portions, said lobes having longitudinally extending reinforcing ribs, certain thereof projecting below the bottom surface of the lobes and providing locking shoulders at their inner ends, inner marginal portions of said lobes being bent outwardly to provide reinforcing abutment flanges; an anchor rod extending through the blade structure between said neck portions, a strain plate secured to the lower end of said rod, said strain plate being adapted to marginally engage the locking shoulders on the lobes whereby to secure said lobes in extended position, a percussion plate having an opening through which the anchor rod extends, said percussion plate being adapted to bear downwardly upon said abutment flanges of the lobes, said percussion plate having depending lugs at opposite ends thereof engaging said neck portions of the lobes.

CHESTER R. PIEPER.
